United States Patent Office.

CHARLES WILHELM AND JOSEPH NEUMANN, OF PHILADELPHIA,
PENNSYLVANIA.

Design No. 2,623, dated April 16, 1867.

DESIGN FOR A SHADE FOR A CEILING LIGHT.

The Schedule referred to in these Letters Patent and making part of the same.

TO ALL WHOM IT MAY CONCERN:

Be it known that we, CHARLES WILHELM and JOSEPH NEUMANN, of the city of Philadelphia, in the State of Pennsylvania, have invented or produced a new and original Design for a Shade for a Ceiling Light, of which the following is a full, clear, and exact description, reference being had to the accompanying drawings, making a part of this specification.

The term "ceiling light," herein used, relates to the modern mode of lighting a church, public hall, or other large building, by transmitting artificial light through suitable openings made for the purpose in the ceiling, and in each of which a flat plate of ground glass is inserted as a shade to prevent the glaring and flickering light which, without it, would be produced.

Our invention consists of a ground-glass shade coextensive with the opening in the ceiling, and having a downward projecting curved or bowl-like form, as shown in the drawings, in which—

Figure 1 is a perspective view of the said shade as applied to a ceiling; and

Figure 2 a vertical diametral section of the same—

Like letters of reference indicating the same parts when in both figures.

In the drawings, A B C is the curved ground-glass shade, and D E a circular moulding which receives the boundary edge of and supports the said shade under the corresponding opening in the ceiling of the building. Any number of the shades A B C, from a large central one to thirty, fifty, or more smaller ones, in accordance with the number of lights to be distributed over the ceiling, are intended to be used.

What we claim as our invention, and desire to secure by Letters Patent, is—

The design for a shade for a ceiling light, herein described and shown.

CHARLES WILHELM,
JOSEPH NEUMANN.
